ADAPTER FOR INSTALLING AN AEROSOL CAN IN A DISPENSING MECHANISM

Richard Emerson, Melville, N.Y., assignor to Auto
Comp Devices, Inc., Lynbrook, N.Y.

Filed Apr. 14, 1972, Ser. No. 244,352

Term of patent 14 years

Int. Cl. D9—01

U.S. Cl. D9—253

FIG.1.

FIG.2.

FIG.3.

FIG.4

FIG. 1 is a top plan view of an adapter for installing an aerosol can in a dispensing mechanism embodying my new design;

FIG. 2 is a front elevational view;

FIG. 3 is a bottom plan view; and

FIG. 4 is a cross-sectional view taken along line 4—4 of FIG. 1.

I claim:

The ornamental design for an adapter for installing an aerosol can in a dispensing mechanism, as shown.
